No. 755,543.

PATENTED MAR. 22, 1904.

J. PUSEY.
SUSPENDERS.

APPLICATION FILED JUNE 16, 1903.

NO MODEL.

UNITED STATES PATENT OFFICE.

JOSHUA PUSEY, OF LIMA, PENNSYLVANIA, ASSIGNOR OF ONE-HALF TO
CHARLES D. WILLIAMS, OF PHILADELPHIA, PENNSYLVANIA.

SUSPENDERS.

SPECIFICATION forming part of Letters Patent No. 755,543, dated March 22, 1904.

Application filed June 16, 1903. Serial No. 161,648. (No model.)

To all whom it may concern:

Be it known that I, JOSHUA PUSEY, a citizen of the United States, residing at Lima, in the county of Delaware and State of Pennsylvania, have invented certain new and useful Improvements in Suspenders, of which the following is a full, clear, and exact description, reference being had to the accompanying drawings, of which—

10 Figure 1 is an elevation showing the device in the normal position when in use. Fig. 2 is a section on line *a a*, Fig. 1. Fig. 3 is a section on line *b b*, Fig. 1. Fig. 4 is a view similar to Fig. 1, showing the position given to 15 the parts in "casting off."

The object of this invention is to provide an improved attachment or cast-off for suspenders, which shall be simple, durable, and whose members are adapted to be readily and quickly 20 connected and disconnected and not liable to become accidentally disconnected.

The leading feature of the invention comprises a button or stud having an enlarged head, which stud is adapted to be fastened to 25 one part of the suspenders, preferably to the trousers straps or connections, and a plate adapted to be fastened to the other part of the suspenders, as the usual elastic webbing, and having an oblique slot adapted to receive 30 the shank of said stud, and which slot has an enlargement at its outer end to allow the passage of the head of the stud, the construction being such, as hereinafter described, that when the stud is entered into said enlarg-

35 ement it may be slid to the bottom of said oblique slot, or caused so to slide, by the stress of the elastic webbing, the head of the stud projecting over the margins of the slot, and when the said plate is brought around from

40 the normal or vertical position to a substantially horizontal position and drawn sidewise the stud may be brought opposite to said enlarged end of the slot and then disconnected from said plate, all as hereinafter described.

45 Other features of the invention relate, respectively, to means for insuring the ready escape of the stud from the said slot and en-

largement and means for preventing the accidental escape of the stud from the latter.

The precise nature of the invention will appear from the following description, reference being had to the accompanying drawings.

Referring now to said drawings, which illustrate that form and construction of the invention which appears to be the most desirable, 55 1 is a stud having an enlarged head 2.

3 is a plate of suitable metal having an oblique slot 4 with an enlargement 5 at its outer end of somewhat greater diameter than the head of said stud, or, preferably, there are 60 two similar convergent slots, as shown, forming a continuous curvilinear or approximately V-shaped slot with the enlargement 5 at each of the outer ends thereof.

The plate member of the device is adapted 65 to be secured to the usual elastic webbing 6 of a suspender—as, for example, by means of a slot 7, through which the webbing is passed—and the stud member is adapted to be fastened (in the present instance riveted) to the usual 70 straps or connections 8, that are buttoned or otherwise fastened to the trousers 9.

In using the device when applied to the suspender parts as mentioned the straps 8 are held in one hand and the elastic webbing and 75 plate are carried into position by the other hand to cause the head of the stud to enter the enlargement 5. On releasing the webbing the shank of the stud will slide down to the bottom of the slot—that is, will occupy the 80 position shown in Fig. 1.

When it is required to disconnect or cast off the parts, the webbing and plate 3 are drawn laterally by the hand or swung in the arc of a circle, or thereabout, to carry the same 85 from the position of Fig. 1 to that of Fig. 4, thus bringing the slot 4—that is, in the present instance the part of the V-shaped slot on that side—to a substantially horizontal plane, and the enlargement 5 opposite to the head of 90 the stud 1, as seen in Fig. 4, thus permitting the stud to pass from said enlargement. When the latter comes opposite the head of the stud, the head will (in the absence of means to pre-

vent it) be apt to project beyond and catch on the margin of the enlargement, thus necessitating manipulation to bring the latter and the head of the stud into accurate registry in order to disconnect the same. To obviate this, I turn up around a part of the enlargement 5 a flange 10, which flange is preferably inclined inwardly, as more clearly seen in Fig. 3. Thus when the stud passes beyond the slot 10 proper of plate 3 its head, impinging against flange 10, is entirely free to escape from the enlargement 5. The inclination of the flange tends to cause the stud to be thrown out of the enlargement automatically—that is, it prevents the edge of the head from catching on the flange through the stress of the elastic webbing. The height of said flange above the surface of the plate with relation to the length of the shank of the stud should be such, as 15 seen in Fig. 2, that the head of the latter cannot project above the flange.

In order to prevent liability of accidental escape of the stud from the slot 4—as, for example, when the wearer of the suspenders 20 bends forward and the strain of the webbing becomes released—I employ a yielding frictional device—as, for example, a suitable spring 11—adapted to bear against the head 2 when the stud is at the bottom of the slot 4, or 25 thereabout. Such spring may be secured to or be an integral part of the plate 3. In the construction shown in the drawings said spring is formed by bending outwardly a part of the wall of the slot, so as to bear against the under side of the head 2, as seen in Fig. 2. By cutting away a part of the plate 3 back of the 30 said margin or throwing out said margin the stress or resistance of the spring may be made as desired—that is, the width and consequent 35 yielding quality of the spring may be made as required.

It is not essential that the spring shall continually press against the stud—that is, press 40 against it when at the bottom of the slot. The location of the spring may be at any point 45 along the length of the slot 4, so that the stud in passing into and out of the slot will depress the spring or push it aside.

Instead of securing the stud to the straps 50 and the plate to the webbing 6 the latter may be attached to said straps and the former to the webbing. This reversal of these parts is, however, not recommended, as it renders their disconnection less convenient than when 55 arranged as shown in the drawings.

It will be seen that in the form of the invention shown in the drawings the cast off 60 may be effected by suitably drawing the suspender-webbing either to the right or to the left, as may be most convenient.

Having thus described my invention, I claim as new and desire to secure by Letters Patent—

1. The combination with suspenders having the usual web portion, and the strap portion

adapted to be secured to the trousers, of the 65 stud secured to said strap portion and having the enlargement on its free end, and the plate secured to said web portion and having the oblique slot adapted to receive the shank of said stud; said slot having an enlargement at 70 its upper end for the passage of said enlargement of the stud, all constructed and adapted to operate substantially as and for the purpose set forth.

2. The combination with suspenders having 75 the usual web portion, and the strap portion adapted to be secured to the trousers, of the stud secured to said strap portion and having the enlargement on its free end, and the plate secured to said web portion and having an 80 oblique slot adapted to receive the shank of said stud; said slot having an enlargement at its upper end for the passage of said enlargement of the stud, together with a spring adapted 85 to prevent the accidental escape of the latter through said enlargement of the slot, all constructed and adapted to operate substantially as and for the purpose set forth.

3. The cast-off device for suspenders comprising the stud, having the enlarged head and 90 adapted to be attached to one part of the suspenders, and the plate adapted to be attached to the other part of the suspenders, and having an oblique slot adapted to receive the shank of said stud, with an enlargement at its outer 95 end for the passage of the head of said shank, together with the upturned flange around a portion of said enlargement, the height of said flange above the surface of said plate being greater than the length of the shank of the stud, 100 substantially as and for the purpose set forth.

4. The cast-off device for suspenders, comprising as one member thereof, the stud adapted to be secured to one part of the suspenders, and as the other member a plate adapted to be 105 secured to the other part of the suspenders, and having the slot adapted to receive the shank of said stud, with the enlargement at its outer end for the passage of the head of the stud, together with the upturned inwardly-inclined 110 flange around a portion of said enlargement, substantially as and for the purpose set forth.

5. The cast-off device for suspenders comprising the stud, adapted to be secured to one part of the suspenders, and having the enlarged 115 head, and the plate adapted to be secured to the other part of the suspenders, and having the approximately V-shaped slot adapted to receive the shank of said stud, with enlargements at the outer ends of said slot for the passage of the head of the stud, substantially as and for the purpose set forth.

6. The cast-off device for suspenders comprising the stud, adapted to be secured to one part of the suspenders, and having the enlarged 120 head, and the plate adapted to be secured to the other part of the suspenders, and having the approximately V-shaped slot adapted to receive

the shank of said stud, with enlargements at its outer ends for the passage of the head of the stud, together with the upturned flange around a portion of said enlargements, and the
5 spring integral with said plate, for preventing the accidental disengagement of the stud from said slot, substantially as set forth.

In testimony whereof I have hereunto affixed my signature this 19th day of May, A. D. 1903.

JOSHUA PUSEY.
